Primary Examiner — Jack Reickel*Assistant Examiner* — Michael A Kervin(74) *Attorney, Agent, or Firm* — Tucker Ellis LLP;
Heather M. Barnes(57) **CLAIM**

The ornamental design for a device for forming soil blocks, as shown and described.

DESCRIPTION

FIG. 1 is a front, top, left perspective view of a device for forming soil blocks showing my new disclosure;

FIG. 2 is a rear, bottom, left perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings represent portions of the device for forming soil blocks that form no part of the claimed design.

1 Claim, 8 Drawing Sheets(56)
